Primary Examiner — T. Chase Nelson*Assistant Examiner* — Mark Cavanna(74) *Attorney, Agent, or Firm* — QuickPatents; Kevin Prince(57) **CLAIM**

I claim the ornamental design for a medallion, as shown and described.

DESCRIPTION

FIG. 1 is a front elevational view of a medallion, showing my new design;

FIG. 2 is a perspective view thereof; and,

FIG. 3 is a top plan view thereof, the bottom plan view, left-side elevational view, and right-side elevational view all being identical.

The broken lines showing a Roman numeral in FIGS. 1 and 2 depict environmental matter and form no part of the claimed design. The rear view forms no part of the claimed design.
